UNITED STATES PATENT OFFICE

EARL RAGON, OF DICKINSON, NORTH DAKOTA

GAS BURNER

Application filed February 17, 1931. Serial No. 516,479.

This invention relates to a gas burner, for either natural or artificial gas, and one that can be placed in any kind of a wood or coal stove or furnace, the general object of the invention being to provide a burner having a frame of any suitable shape to conform to the fire box of a furnace or stove, and provided with a plurality of jets so formed and shaped as to direct the flame against the sides 10 of the furnace as to produce the maximum amount of heat, with the minimum amount of fuel.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, in which:—

Figure 1 is a plan view of the invention.

Fig. 2 is a front view thereof with the supply pipe in section.

Fig. 3 is a section on the line 3—3 of Fig. 1.

Fig. 4 is a section on the line 4—4 of Fig. 1.

In the drawings, the numeral 1 designates the frame of the burner of rectangular shape in the drawings, but which of course may be of circular shape or other shapes, so as to conform to the shape of the fire box in which it is to be placed. Each side member of the frame is of course, of tubular construction, and a plurality of small pipes or tubes 2 projects from the top of the frame, these tubes 35 being threaded into holes in the frame part, or otherwise attached to the frame part with the tubes in communication with the interior of the frame.

After the tubes are put in place, they are 45 bent outwardly, so that the flames produced by the burning gas escaping from the tubes will be directed against the walls of the furnace, thus producing the maximum amount of heat with the minimum amount of fuel.

50 A coupling 5 is welded or otherwise con-

nected to the central part of one of the members of the frame, and a short length of pipe 6 is threaded into the coupling. A small supply pipe 7 has one end extending into the pipe 6, and is spaced therefrom by the spacers 55 8 so that air can enter the outer end of the pipe 6 through the space formed by said pipe and the pipe 7, and thus mixed with the gas and air flowing from the pipe 7. The outer end of the pipe 7 has attached thereto any desired type of air mixer 9 and the low pressure gas line is shown at 10 for introducing gas through the nozzle 11 into the air mixer.

This device is adapted to be placed in the fire box of a stove or furnace on a flooring 65 of tin or the like, so as to keep the air from coming up through the bottom part of the fire box.

It is thought from the foregoing description that the advantages and novel features 70 of the invention will be readily apparent.

It is to be understood that changes may be made in the construction and in the combination and arrangement of the several parts, provided that such changes fall within 75 the scope of the appended claim.

Having thus described my invention, what I claim as new is:—

A burner for the firebox of a furnace comprising a frame of rectangular shape and 80 each member thereof being formed of tubular stock, a plurality of small burner tubes connected with the top of each member of the frame and in communication with the interior thereof and extending upwardly and outwardly to direct the flames against the walls of the firebox, each burner tube being formed of a single piece of tubing of the same diameter throughout, a coupling fastened to the front of one of the members of the frame, 85 a large pipe threaded in the coupling, a small pipe extending into the outer end of the large pipe, and spaced therefrom and means for introducing a mixture of air and gas into 90 the outer end of the small pipe.

In testimony whereof I affix my signature.
EARL RAGON.
